UNITED STATES PATENT OFFICE

2,048,670

POWDER DISPENSER

Albert Berger, Brooklyn, N. Y.

Application April 8, 1935, Serial No. 15,236

7 Claims. (Cl. 221—64)

This invention relates to powder dispensers. It is an object of the invention to provide a powder dispenser adapted to be mounted upon a wall or other convenient support operable automatically 5 to deposit powder along the bristles of a tooth brush upon mere insertion of the brush into the lower part of the dispenser.

It is a feature of the invention that provision is made of valve means for controlling the discharge of powder from an inverted powder can and that mechanism is provided which is adapted to be engaged and driven by the body or back of the toothbrush for opening the valve to permit the powder to fall on the bristles of the brush.

It is a further feature of the invention that the valve is automatically returned to closed position as the brush is withdrawn.

Other objects and advantages will hereinafter appear.

20 In the drawing forming part of this specification,

Fig. 1 is a fragmentary view in elevation, partly broken away, illustrating a dispenser embodying features of the invention and having an inverted powder can set in it;

Fig. 2 is a detail sectional view taken on the line 2—2 of Fig. 1 looking in the direction of the arrows;

Fig. 3 is a fragmentary perspective view showing the powder can and the dispenser; and

Fig. 4 is a fragmentary view showing a detail of the mounting of the valve operating mechanism.

A powder can 1 is shown in Fig. 1 as set in inverted position in a dispenser 2. The dispenser comprises side body members 3 and 4 which are connected by a front plate 5 and a back plate 6. The back plate 6 is provided with flanged ears 7 which are adapted to be fitted onto headed screws 40 or other suitable supporting members secured in a wall.

The upper portions of the body members come together and jointly form a circular seat 8 upon which a shoulder of the can rests. They also cooperate to form a circular seat 9 upon which a funnel-like discharge spout 10 is rotatably mounted. The discharge spout 10 has a circular opening in the upper portion thereof for receiving the mouth of the powder can. The discharge spout is provided in the throat portion thereof with inclined ribs 12 for stirring the powder to prevent choking or clogging. A gear 13 is formed upon or affixed to the exterior of the discharge spout 10 and is adapted to be driven by a pinion 14 fixed upon the upper end of a shaft 15. The

shaft 15 carries a supporting collar 16 which rests upon a shelf 17 formed on the body member 4. Beneath the shelf 17 provision is made of a valve plate 18 fast upon the shaft 15 which normally covers and closes the exit opening at the lower end of the discharge spout 10. A spring 19 secured at one of its ends to the shaft 15 and at the opposite end to the body member 4 serves to retain the plate 18 normally in spout closing position. At the lower end of the shaft 15 provision is made of a wheel 20 having a ring 21 of rubber or other suitable friction material secured upon it. The wheel 20 is secured through a spring 22 to a short shaft 23, the latter being adapted to snap into a bearing recess in the bottom wall 24 of the 15 body member 4.

The body member 5 is provided with a groove 26 in opposed relation to the ring 21. The ring 21 is provided with a corresponding groove 27. These grooves are adapted to embrace the opposite sides of the back of a toothbrush and fit snugly against such sides. The front plate 5 is provided with an opening 28 in the lower portion thereof in line with the passage between the grooved wall 26 and the grooved ring 21 so that a toothbrush may be inserted into the device. When the toothbrush is inserted the grooved wall 26 causes the back of the brush to be pressed into frictional driving engagement with the grooved ring 21 so that the shaft 15 is turned against the 25 resistance of the spring 19. This turns the valve plate 18, causing it to uncover the exit opening of the discharge spout 10 and permits the powder to fall onto the brush. The pinion 14 at the same 30 time drives the discharge spout through the gear 13 causing the stirrer blades 12 to agitate the powder. The inclination of the blades is such 35 that they tend to force the powder downward as the toothbrush is thrust in.

The powder falls onto the toothbrush bristles 40 so long as the valve plate is open. It is only necessary to thrust the toothbrush into the dispenser and immediately withdraw it in order to cause the desired amount of powder to be deposited. As the toothbrush is withdrawn the valve 45 plate is returned to closed position and is retained in the original closed position by the action of the spring 19.

In the assembly of the device the shaft 15 and the parts rotatable with it are assembled as a unit. 50 They are then associated with the body member 4, the shaft being inserted into a notch 29 formed in the shelf 17 and the pivot pin or shaft 23 being snapped into the recess 24. The body members 3 and 4 may next be connected through 55

the front and back plates 5 and 6 by means of screws 30 and 31, and the discharge spout 10 may then be put into place to complete the assembly. The device is now ready to be hung on the wall 5 and to have a powder can associated with it in the manner illustrated in Fig. 1.

While I have illustrated and described in detail a preferred form of my invention, it is to be understood that changes may be made therein 10 and the invention embodied in other structures. I do not, therefore, desire to limit myself to the specific constructions illustrated, but intend to cover my invention broadly in whatever form its principle may be utilized.

15 I claim:

1. In a powder dispenser, the combination, with a discharge spout, of means for controlling the discharge of powder from the spout comprising a valve, means adapted to be actuated by the thrusting of a tooth brush beneath the spout for opening the valve, and means for automatically closing the valve when the tooth brush is withdrawn, said valve opening means comprising a brush engaging guide, a friction roller opposed thereto, and an operating train interposed between the roller and the valve.

2. In a powder dispenser, the combination, with a discharge spout, of means for controlling the discharge of powder from the spout comprising a valve, means adapted to be actuated by the thrusting of a tooth brush beneath the spout for opening the valve, and means for automatically closing the valve when the tooth brush is withdrawn, said valve opening means comprising a friction roller and a shaft on which the roller is mounted, the valve being in the form of a plate secured upon and rotatable with the shaft.

3. In a powder dispenser, the combination, with a discharge spout, of means for controlling the discharge of powder from the spout comprising a valve, means adapted to be actuated by the thrusting of a tooth brush beneath the spout for opening the valve, and means for automatically closing the valve when the tooth brush is with-

drawn, said valve opening means comprising a friction roller and a shaft on which the roller is mounted, the valve being in the form of a plate secured upon and rotatable with the shaft, and gearing interposed between the shaft and the 5 spout for rotating the spout, the spout having stirrer blades provided internally thereof.

4. In a powder dispenser, in combination, a casing, a rotary spout seated therein and having stirrer blades provided within it, a valve controlling the discharge of powder from the spout, and means automatically actuated upon insertion of a tooth brush beneath the spout to open the valve and rotate the spout.

5. In a powder dispenser, in combination, a cas- 15 ing, a discharge spout, a valve plate disposed across the spout, a shaft carrying said valve plate, a roller on the shaft, means for guiding a tooth brush in frictional engagement with said roller, a spring normally urging the shaft to valve clos- 20 ing position, a pintle pin carried by the shaft and a compressible spring interposed between the pintle pin and the shaft, said casing having a 25 socket into which the pintle pin is adapted to be snapped.

6. In a powder dispenser, in combination, a cas- 30 ing, a rotary spout seated therein and having stirrer blades provided within it, a valve controlling the discharge of powder from the spout, and means automatically actuated upon insertion of a tooth brush beneath the spout to open the valve and rotate the spout, said casing being formed to receive and support an inverted powder can and being provided with means for facilitating at- 35 tachment of the casing to a supporting wall.

7. In a powder dispenser, in combination, a casing, a rotary spout seated therein, and having stirrer blades provided within it, a valve controlling discharge of powder from the spout, means for opening the valve, and means automatically 40 actuated upon operation of the valve opening means to rotate the spout.

ALBERT BERGER.
